R. Wheeler & S. A. Bailey
Design for Stove
Patented May 19, 1857

Pat 887

Rufel Wheeler & Stephen A. Bailey, of Utica, N.Y.
Letters Patent, No 887. Dated May, 19, 1857.

The schedule referred to in these Letters Patent, and making part of the same.

To all whom it may concern:

Be it known that we, Rufel Wheeler & Stephen A.

Dec 887

Bailey, of the city of Utica, in the County of Oneida, and State of New York, has invented or produced a new and original design for the external configuration of a Cooking Stove, which we have denominated the "Rival Cook," and we do hereby declare, that the following is a full and exact description of the same, reference being had to the annexed drawings, and to the letters of reference marked thereon:

In which Fig: 1, exhibits a perspective elevation of the stove showing substantially the ornamental configuration of its surface.

The front end and one side are here shown. The opposite side is like the one here seen. The figures on the plates are in basso-relievo. There are three doors A, B, C, on each side of the stove, ornamented in one rectangular panel each. C, is the door to the fire place; and A and B, both open into the oven. The character of the ornaments on the door A, is similar to that of those on the door B, differing mainly on account of the difference in the size of the doors. The figure upon the door C, is different, and is shown substantially in the drawing. Above a plate immediately over the door B, in raised letters is the appellation given to the stove "Rival Cook."

The front plate D, above the hearth is divided into two panels, both of which are similarly ornamented, as shown in the drawing. Under the hearth the front plate P, is plain with simply a bead crossing it diagonally. The body of the hearth is without ornament, but an ornamented border E, K, surrounds it on three sides, consisting of consecutive clusters of flowers, as shown. The top plate F, is without ornament; but its edge is ornamented quite round, by raised curves and points, alternating with each other, as shown in the figure.

There is also an ornamented border H, quite round upon the edge of the bottom plate, cut into pointed figures as shown. The back end plate not seen in the figure is divided into two rectangular panels, but without ornament.

Fig: 2, represents a quarter section of the door B, (Fig 1), on an enlarged scale, with a view to show the configuration more distinctly. And Fig: 3, is a like representation of the end K, of the border E, K, (Fig. 1) of the hearth.

3

Des. 887

We claim as new and desire to secure by Letters Patent, the
designs involved in the ornamenting of a stove by the estimated configuration
thereof, substantially as herein set forth.
